US00D883728S

(12) **United States Design Patent** (10) Patent No.: **US D883,728 S**
(45) Date of Patent: **** May 12, 2020**

(54) **KETTLE**

(71) Applicants: **Leslie Alexander Gort-Barten**,
Crawley (GB); **Alex Gort-Barten**,
Crawley (GB)

(72) Inventors: **Leslie Alexander Gort-Barten**,
Crawley (GB); **Alex Gort-Barten**,
Crawley (GB)

(**) Term: **15 Years**

(21) Appl. No.: **35/504,365**

(22) Filed: **Aug. 1, 2017**

(80) **Hague Agreement Data**

Int. Filing Date: **Aug. 1, 2017**

Int. Reg. No.: **DM/098397**

Int. Reg. Date: **Aug. 1, 2017**

Int. Reg. Pub. Date: **Feb. 2, 2018**

(30) **Foreign Application Priority Data**

Feb. 3, 2017 (EM) 003738228

(51) LOC (12) Cl. **07-99**

(52) U.S. Cl.

USPC **D7/317; D7/319**

CPC ..... **A47J 31/00 (2013.01)**

(58) **Field of Classification Search**

USPC D7/316-321, 378, 384, 598, 600, 619.1,
D7/622; D9/544, 545, 548, 549

CPC A47J 31/00; A47J 27/21; A47J 27/21008;
A47J 27/21041; A47G 19/22
